AXEL G. BERGMAN, OF NEW YORK, N. Y., ASSIGNOR TO ORDNANCE ENGINEERING CORPORATION, OF NEW YORK, N. Y., A CORPORATION OF NEW JERSEY.

ILLUMINATING-SHELL.

1,318,720.

Specification of Letters Patent. Patented Oct. 14, 1919.

Application filed January 10, 1918. Serial No. 211,141.

To all whom it may concern:

Be it known that I, AXEL G. BERGMAN, a subject of the King of Sweden, residing in the borough of Manhattan, city, county, and 5 State of New York, have invented certain new and useful Improvements in Illuminating-Shells, of which the following is a specification.

This invention relates to illuminating shells and is in the nature of an improvement on the structure disclosed in my pending application filed September 11, 1916, Serial No. 119,396.

The primary purpose of the present structure is to reduce the cost of manufacture and simplify the construction and assembling of the different parts, and thereby bring the product within the bounds of commercial and practicable requirements.

20 The structure to which the invention is applied embodies a projectile device that is discharged from a mortar or other suitable apparatus and remains suspended in the air, more or less at one point, while burning for 25 a predetermined period either for giving a signal or disclosing the ground outline under the lighted area, and a further object of the invention is to afford instrumentalities that will permit supporting the 30 illuminating charge from a parachute structure and also eliminate likelihood of breaking or damaging the parachute while it is unfolding, and immediately after the shell is discharged, at which time it is traveling 35 at a high rate of speed with a resulting tendency to rupture the parachute.

An additional purpose of the invention is to preclude the premature ignition of the illuminating charge, and insure the delaying 40 of such ignition until after the illuminating charge leaves its container or shell.

Another purpose of the invention is to regulate the control of the time fuse, which determines the period that precedes ignition 45 of the illuminating charge, so that the predetermined time, after which the illuminating charge comes into play, can be adjusted with considerable accuracy, and to accomplish this by protecting the fuse against an 50 excessive pressure at the moment of discharging the shell from the mortar.

Still an additional purpose of the present improvement is to afford a more effective illuminating composition by increasing the

possible candle power per second, and further, to provide a more intimate relationship between the illuminating compound and the igniting element and thus obtain practically instantaneous ignition of the entire illuminating surface. To these and other ends the 55 invention consists in certain other improvements and combinations of parts as will be hereinafter more fully described and particularly pointed out in the claims following the specification.

In the drawings,—

Figure 1 is a longitudinal sectional view illustrating a preferred embodiment of the invention;

Fig. 2 is an end elevation, and

Fig. 3 is a sectional view in a horizontal plane, taken on the line 3—3 of Fig. 1.

My invention consists generally of an outer jacket or shell having a fixed closure at one end which is preferably in the form 75 of a sheet metal stamping, containing a fuse and fuse-holding tube. The jacket contains a carrier that is attached to a parachute, and holds the illuminating charge, and the connection between the carrier and the parachute is such as to permit the latter to respond gradually to the movement of the carrier. The carrier, with the parachute attached, is adapted to be ejected from the jacket or shell by an expelling charge which 80 is located on the inner surface of the closure referred to, while the outer surface of said closure serves as a housing for a time fuse which communicates with the expelling charge. Movable secured to the outer face 85 of the closure is a shield member that is adjustable over the fuse and protects the latter at the point of ignition against the full force of the discharging pressure, as the shell is thrown from the mortar.

It is to be understood that the different features of my improvement are susceptible of various practical adaptations, and in its preferred form the structure includes an outer shell or jacket A within which is contained the carrier B that serves as a housing or holder for the illuminating charge C. Disposed at one end of the jacket A is a closure which is fixed to the jacket and designated generally by D. The closure D is 100 preferably formed of sheet metal by a suitable stamping operation and includes circular corrugations E and F affording an in-

terior pocket or recess F' and an exterior pocket or recess E'. Arranged in the interior pocket F' is a carrier expelling charge G, while H designates a fuse that is disposed in the exterior pocket E'. The fuse is inclosed in a puncturable tube, as in my previous application already referred to, and is of a slow burning character, so that the point of ignition of the fuse, which is determined by puncturing the surrounding tube at any selected point, controls the time that is required to ignite the expelling charge G. The fuse H communicates with the expelling charge G through an opening formed in the side wall of the corrugation E of the closure. By thus arranging the expelling charge and the fuse in opposite surfaces of the closure D, I provide an extremely economical arrangement which is comparatively simple to manufacture and also affords an efficient operation.

It is quite desirable to prevent the fuse, at the point where it is ignited, from being subjected to excessive pressure, as this will frequently cause a quick burning out of the fuse through its entire length, and the chief desideratum is to present sufficient heat to cause ignition and yet permit the fuse to burn in the normal or expected time. To this end I employ retaining means, preferably in the form of a plate I, which is provided with a series of openings I' through which the fuse tube can be punctured at any point, depending upon the time that it is desired to delay the illuminating action. Coöperating with the retaining plate I is a shield J which is adjustable, and positionable over any one of the openings I', or the point of ignition of the fuse. The retaining plate I and the shield J are held in place by a bolt K extending through the closure D from the inner surface thereof and receiving a securing nut L on its outer end. The inner portion of the shank of the bolt K is squared or otherwise formed in cross-section to prevent relative turning of the closure D and retaining plate I, while the shield J is free to turn upon the retaining plate I about the axis of the bolt K, and is held in adjusted position by its frictional engagement.

The inner surface of the shield J is provided near its outer end with a lateral passage M, preferably formed by stamping the shield outwardly at this point, and the passage M extends from one edge of the shield to the other, as shown in Fig. 2. This affords a means of communication between the opening I', which underlies the shield, and the edges of the shield, so that as the shell is discharged from the mortar, the heat set up travels through the lateral passages M and thus reaches the fuse at the point where its containing tube has been punctured and ignites it. In the operation of this part of the structure, the fuse-containing

tube is first punctured at the selected point and the shield is then adjusted over such point, that is, over the selected opening I' in the retaining plate, and the shell is then placed in the mortar to be discharged. 70 While this arrangement permits igniting the fuse, the shield adequately protects the punctured part of the fuse casing against any direct pressure, and obviates the possibility of an excessive pressure gaining access 75 to the fuse at this point and causing its premature burning.

N designates an igniting charge which is arranged in juxtaposition to the illuminating charge C, preferably as a base, or disk at 80 one end, while N' are projections or extensions, preferably elongated, and forming part of the igniting charge which extends into openings in the illuminating charge. This provides a more intimate relation 85 between the igniting and illuminating charges and insures quick ignition of the latter. O is a disk arranged adjacent to the igniting charge N and provided with a series of openings O'. The disk O is located in the end 90 of the carrier B, and P is a second disk arranged in the jacket A adjacent to the end of the carrier B and having a series of openings P' coincident with the openings O'. Q is a spacing plate positioned between the 95 disk P and the closure D and having a central opening Q'. Positioned between the spacing plate Q and the disk P is a quickly-igniting charge R of mealed powder which is ignited immediately after the carrier B 100 is discharged from the jacket A. In the operation of this part of the structure, the shell is initially discharged from the mortar, as already described, and after the fuse is burned for the predetermined period, the expelling charge G is ignited, causing the carrier B to be discharged from the jacket A. Immediately as this takes place, the mealed powder charge R starts to burn, setting off the igniting charge N, and this in turn ignites the illuminating charge. The corrugation F engages the spacing plate Q and thus 105 separates the expelling charge F' from the central opening Q' in the spacing plate, so that there is no opportunity for the igniting 110 charge to be set off until the carrier B is expelled from the jacket A.

A parachute is arranged within the jacket A, which is designed to be unfolded by the air resistance when it and the illuminant 115 body C are ejected from the jacket A. A removable closure S normally maintains the parachute and illuminant in place. For short ranges the speed of the projectile is not ordinarily so great as to disrupt the 120 parachute, but for greater ranges the momentum of the illuminant body is apt to be so great when it is ejected at any intermediate point that the wind pressure becomes excessive on the parachute and it is apt to im- 125 130

mediately slit or tear, thereby destroying its utility. According to the present invention, I interpose between the parachute a shock-absorbing device which is designed 5 to ease the strain between the parts until the inertia of the illuminant is partly or wholly overcome. In a device of this character it is highly desirable that such shock-absorbing device shall be of the utmost simplicity and cheapness possible with the necessary certainty of operation. Hence, according to the preferred form of the invention I make use of a wire which is preferably folded or coiled into spiral form, preferably 10 in the helical shape shown in the drawing at U. One end of this wire is attached to the illuminant by a disk U' engaged by the housing B, and the other end is connected to the usual cords of the parachute. Such 15 wire may have a certain amount of springiness or elasticity, but the chief function it performs is that of dissipating the inertia of the illuminant, and ordinarily it is better to avoid such reactions as would come 20 from a spring. Hence, I preferably employ a soft metal wire which has little or no spring action, but a certain resistance to bending, so that it requires an appropriate amount of force to straighten it. When so 25 formed there is little or no tendency for the wire to again assume its coiled condition. Sudden strains upon the parachute are hence avoided, thus enabling the illuminant to be projected when the shell is moving at considerable 30 velocities without endangering the structure of the parachute.

Arranged between the removable closure S and the carrier B are supporting members V, preferably in the form of substantially 35 semi-circular walls, one end of which engage 40 the end of the carrier B and the other end of which engage the removable closure S, which latter is ejected from the jacket A along with the paraehute and illuminating 45 charge. The supporting walls V relieve the jacket A from the pressure caused by atmospheric resistance to the travel of the shell, as the latter is discharged, and any such 50 pressure is transmitted through the walls V to the solid illuminating body C, and consequently no strain is exerted on the outer jacket A. The walls V also force the removable closure S from the jacket when the parts are discharged, and protect the para- 55 chute fabric against strain or pressure.

No illuminating compounds have been developed heretofore with candle powers that were not relatively low, and I have discovered that the candle-power can be materially 60 increased, without reducing the time of burning, by subjecting the compound to proper action of heat and pressure. For this purpose, I may employ barium nitrate and aluminum, with perchlorid potassium or po- 65 ssium nitrate, and a binder, either shel-

lac or resin, although the latter is preferred as it is more economical and produces less smoke than shellac. This treatment gives an enormous increase in candle power, and with a standard size shell illuminant, having 70 a diameter of about 1 $\frac{1}{8}$ inches, a candle power of 100,000 to 125,000 burning for a period of thirty seconds, is possible, whereas previously nothing greater than 8000 candle power could be obtained. The time of burning is governed largely by the degree of pressure applied to the mixture, and the cross sectional area, and these factors can be varied as desired. The best results thus far obtained are based on a combination of 80 barium nitrate, coarse aluminum, fine aluminum and resin, in proportions of 67% 16.6%, 12.4%, and 4%, respectively. This composition may be varied as to specific proportions within certain limitations, and the 85 most effective treatment is by heating the composition to 100° C. It is then packed in a container, and rammed by hand. The composition thus packed is subjected to a pressure of about 1200 pounds per square 90 inch for a period of approximately three minutes, and the illuminant is then ready to be packed in the jacket or shell, and will give the results already noted.

I claim:

1. The combination with a jacket, of a carrier adapted to be discharged from the jacket, a closure at one end of the jacket having recesses or pockets in its opposite surfaces, a carrier expelling charge located 100 in a recess on the inner surface of the closure, and a fuse positioned in a recess in the outer surface of the closure and communicating with said expelling charge.

2. The combination with a jacket, of a 105 carrier adapted to be discharged from the jacket, a closure at one end of the jacket provided with corrugations affording interior and exterior recesses or pockets, a carrier expelling charge located in an interior 110 pocket and a fuse located in an exterior pocket and communicating with said expelling charge.

3. The combination with a jacket, of a carrier adapted to be discharged from the 115 jacket, and a closure at one end of the jacket having provision for housing an expelling charge on its inner surface and a fuse on its outer surface, one end of the fuse being in communication with said expelling charge.

4. The combination with a jacket, of a carrier adapted to be discharged from the jacket, an expelling charge positioned within the jacket, a closure containing a fuse in 125 communication with said expelling charge, retaining means for the fuse, and an adjustable shield positionable over the fuse at its point of ignition.

5. The combination with a jacket, of a 130

- carrier adapted to be discharged from the jacket, an expelling charge positioned within the jacket, a fuse communicating with the expelling charge, and an adjustable shield positionable over the fuse at its point of ignition. 6. The combination with a jacket, of a carrier adapted to be discharged from the jacket, an expelling charge positioned within the jacket, a fuse communicating with the expelling charge, a retaining plate overlying the fuse and having openings through which the fuse is accessible, and a shield rotatively mounted on said plate and movable to a position over any of the aforementioned openings, the opening underlying the shield communicating with a lateral passage formed in the shield between it and the retaining plate. 7. The combination with a jacket, of a carrier adapted to be discharged from the jacket, a closure at one end of the jacket provided with circular corrugations affording interior and exterior recesses or pockets, a carrier expelling charge located in one of the interior pockets and a fuse located in one of the exterior pockets and communicating with the expelling charge, a retaining plate attached to and overlying the closure, and having openings through which the fuse is accessible, and a shield rotatively mounted on said plate and movable to a position over any of the aforementioned openings, the opening underlying the shield communicating with a lateral passage formed in the shield between it and the plate. 8. The combination with a jacket, of a carrier adapted to be discharged from the jacket, an illuminating charge contained in the carrier, and an igniting charge located adjacent to one end of the illuminating charge and including a plurality of projections extending into openings in the body of the illuminating charge. 9. The combination with a jacket, of a carrier adapted to be discharged from the jacket, an illuminating charge contained in the carrier and an igniting charge in the form of a disk or base located adjacent to one end of the illuminating charge and including a plurality of elongated projections extending into openings in the body of the illuminating charge. 10. The combination with a jacket, of a carrier adapted to be discharged from the jacket, an illuminating charge contained in the carrier, an igniting charge disposed adjacent to the illuminating charge, a closure for the jacket, a spacing wall separating the closure from the igniting charge and having an opening therein, an expelling charge located between said wall and the closure, and an abutment which separates said expelling charge from the opening in the spacing wall until after the carrier is partially expelled. 11. The combination with a jacket, of a carrier adapted to be discharged from the jacket, an illuminating charge contained in the carrier, an igniting charge disposed adjacent to the illuminating charge, a closure for the jacket, a spacing wall separating the closure from the igniting charge and having a central opening therein, and an expelling charge located between said wall and the closure, the latter having a circular corrugated portion which abuts against the spacing wall and separates the expelling charge from said central opening until after the carrier is partially expelled. 12. The combination with a jacket, of a carrier adapted to be discharged from the jacket, an illuminating charge contained in the carrier, an igniting charge disposed adjacent to the illuminating charge, a disk in the end of the carrier having openings communicating with the igniting charge, a disk in the jacket arranged adjacent to the last mentioned disk and having corresponding openings, a closure for the jacket, an expelling charge adjacent to the closure, a spacing plate positioned between the expelling charge and the ignition charge and having an opening therein, and a charge of mealed powder arranged between the spacing plate and the aforesaid disks. 13. The combination with a jacket having a fixed closure at one end, of a carrier adapted to be discharged from the jacket, an expelling charge positioned between said closure and the carrier, a movable closure at the opposite end of the jacket adapted to be discharged with the carrier, a parachute attached to the carrier and positioned between it and said movable closure; and a plurality of supporting members contacting at one end with the carrier and at the other end with said movable closure. 14. The combination with an illuminant body and a parachute, of a shock absorbing device connecting them and acting to permit the parachute to gradually respond to the inertia of the illuminant body. 15. The combination with a parachute and an object adapted to be carried by it, of a connection between them comprising a metallic coil which offers sufficient resistance to uncoiling to cause a gradual response by the parachute to the inertia of said object. 16. The combination with a jacket, of a carrier adapted to be discharged therefrom, an illuminating charge contained in the carrier, and a parachute connected to the carrier by an elastic metallic coil which offers sufficient resistance to uncoiling to cause the parachute to respond gradually to the inertia of the carrier.

17. In combination with a projectile, an illuminant, a parachute, means for expelling the illuminant and parachute from the projectile, and a substantially non-reactive shock-absorbing member connecting the illuminant and parachute.

18. The combination with a projectile, of an illuminant body and a parachute adapted to be ejected from the projectile, and means connecting the illuminant body and para-

chute, and acting to permit the parachute and illuminant body to be expelled from the projectile while the latter is traveling at high speed, and to cause the parachute to respond gradually to the inertia of the illuminant body.

In witness whereof, I have hereunto signed my name.

AXEL G. BERGMAN.
